UNITED STATES PATENT OFFICE.

STEPHEN VARNI, OF BROOKLYN, NEW YORK.

DESIGN FOR A SETTING FOR JEWELRY.

Application filed March 12, 1927. Serial No. 21,123. Term of patent 7 years.

To all whom it may concern:

Be it known that I, STEPHEN VARNI, a citizen of the United States, and resident of the borough of Brooklyn, county of Kings, city and State of New York, have invented a new, original, and ornamental Design for a Setting for Jewelry, of which the following is a specification, reference being had to the accompanying drawing, forming part thereof.

Fig. 1 is a face view of a setting exhibiting my new design (both faces of said setting being alike), and Fig. 2 is an edge view of such setting looking in the direction of arrow 2 of Fig. 1.

I claim:

The ornamental design for a setting for jewelry, as shown.

STEPHEN VARNI.
